OTTO PROCHAZKA, OF DETROIT, MICHIGAN.

PLUG.

1,121,664.

Specification of Letters Patent. Patented Dec. 22, 1914.

Application filed February 13, 1914. Serial No. 818,456.

To all whom it may concern:

Be it known that I, Otto PROCHAZKA, a citizen of the United States of America, residing at Detroit, in the county of Wayne 5 and State of Michigan, have invented certain new and useful Improvements in Plugs, of which the following is a specification, reference being had therein to the accompanying drawings.

10 My invention relates to plugs for electrical sockets and has among the objects thereof to provide a plug which may be easily and quickly engaged with or disengaged from the socket; to provide such a 15 plug that may be positively locked within the socket; and further to provide a simple and efficient structure that may be easily and cheaply manufactured.

Other objects of the invention will more 20 fully hereinafter appear.

The invention resides in the peculiar construction, arrangement and combination of parts as hereinafter set forth and particularly pointed out in the claims.

25 In the drawings, Figure 1 is a perspective view of the device embodying the invention; Fig. 2 is a longitudinal, sectional view through the plug; Fig. 3 is a view partly in section, showing the plug engaged with 30 the socket; and Fig. 4 illustrates a detail of construction.

A designates the body of the plug and B the portion adapted to be inserted into the socket C, both the body A and the portion 35 B being formed of suitable insulating material and being of suitable configuration.

D is the usual spring contact at the inner 40 end of the plug and is electrically connected to a binding post or terminal E by means of a metallic strip F with which the binding post—herein shown in the form of a screw—has a threaded engagement. The connection between the contact D and the terminal E, however, may be of any suitable construction. F' is the other contact which is 45 preferably in the form of a threaded metallic segment connected to or embedded in the side of the portion B, and G is a binding post electrically connected to the segment F' as by means of a metallic strip H. The latter has a laterally-extending portion I at its inner end which is threaded to receive the screw or post G and has its outer end 50 electrically connected with the segment F' as by being soldered thereto. The body A is provided with an opening J to permit the

cord or wire K to extend within the chamber L. The wires of the cord are connected to the binding posts E and G in the usual manner and preferably the chamber L is of a size to allow a knot M to be formed 60 in the cord so as to prevent any stresses on the cord being transmitted to the binding posts. In the construction illustrated, the body portion has a removable part or cap N which is held in place by a screw O. Thus by removing the screw O the cap N may be detachable and access be given to the interior of the body portion to permit the wires to be engaged or disengaged from the 65 binding posts.

In plugs now in quite common use, the plug is provided with a contact corresponding to the contact F, which is in the form of a threaded ring so as to permit the plug 70 to be screwed into engagement with the socket. With such a type of plug the latter is not readily engaged with or detached from the socket. I have therefore provided a construction which will permit the 75 plug to be easily and quickly engaged with or disengaged from the socket and which may be applied to the standard socket now in general use. Thus as before stated, the contact F' is in the form of a screw-threaded 80 segment and is arranged upon one side of the portion B. Upon the opposite side of the portion B is positioned a member P preferably in the form of a segment having threads complementary to the threads of the 85 socket. The portion of the member B adjacent the member P is cut away as at A² to permit of movement of the member P. This member is attached to a laterally-extending arm O' upon an actuating rod P' 90 that has the outer end projecting beyond the body portion A so as to permit the rod to be actuated. In the particular form illustrated the rod P' is arranged at an angle to the axes of the portion B and is normally 95 held in its outward position of adjustment by means of a spring Q having one end engaging the base R of a chamber S in the portion A and having its opposite end abutting against a collar T fixed on the rod. The 100 member T preferably has a threaded engagement with the outer end of the rod, which will permit the tension of the spring to be varied.

U is a button swiveled upon the outer 110 end of the projection V of the rod P'. With the construction described, when it

is desired to engage the plug with the socket, the operator presses inwardly upon the button U, which moves the rod P' inwardly against the tension of the spring S and shifts the locking member P to the position shown in dotted lines in Fig. 2. In this position the distance between the members F' and P is less than the diameter of the threaded portion of the socket, and the plug 10 may be therefore readily inserted longitudinally within the socket. When so inserted the operator releases the button U and the spring Q moves the rod P' outwardly, which will cause the segments F and P to engage 15 the threaded portion of the socket. To remove the plug it is merely necessary to press inwardly upon the button U and then by a longitudinal movement of the plug the latter may be readily withdrawn from the socket. 20 The member P preferably is formed of metal but is not in the electrical circuit. Therefore the coöperating contacts for engaging the socket are fixed in position upon the plug, eliminating any movable parts in 25 the electrical circuit through the plug.

While the tension of the spring Q is such as to prevent the plug being pulled out of the socket by any normal stress upon the cord, however, quite frequently heavy 30 shades are suspended from the socket by means of a cord and I have, therefore, provided means for positively locking the plug within the socket. The preferred form of this means comprises an eccentric portion 35 W upon the button U, which upon the turning of the button will engage with a bearing or abutment X on the body A and positively lock the rod P' against inward movement, thereby preventing any inward movement of the section P. The bearing X is 40 preferably slightly inclined, so that upon the turning of the button there will be a tendency to draw the rod P' outward, which will tend to increase the distance between 45 the members F and P.

While I have illustrated and described the mechanism which permits the plug to be engaged with the socket by a longitudinal movement in connection with my improved 50 form of plug, I do not desire to limit my protection to any particular type of plug, since it is readily apparent that such mechanism may be applied to various plug constructions. Also while I have shown and 55 described the preferred form of the invention, I do not desire to limit my protection to the particular arrangement of parts illustrated, but consider the invention to be 60 broad enough to embody various modifications.

What I claim as my invention is:—

1. A plug comprising a socket-engaging portion, a body portion, contacts carried by the socket-engaging portion, an adjustable member on the socket-engaging portion for

engaging the socket, and a push rod movable longitudinally of the plug extending out through the body portion and arranged at an angle to the longitudinal axis of the plug, said push rod having one end attached 70 to said adjustable member, the other end extending out through the body portion.

2. A plug comprising a socket-engaging portion, a body portion, contacts carried by the socket-engaging portion, an angularly 75 movable engaging member on the socket engaging portion, and a push rod movable longitudinally of the plug extending out through the body portion and arranged at an angle to the longitudinal axis of the 80 plug, said rod being provided with a laterally-extending arm at its inner end connected to said engaging member, the other end of the push rod extending out through the body portion. 85

3. A plug comprising a socket-engaging portion, a body portion, contacts carried by the socket-engaging portion, an angularly 90 movable locking member on the socket engaging portion, a push rod extending out through the body portion and arranged at an angle to the longitudinal axis of the plug, said rod being provided with a laterally-extending arm at its inner end connected to said locking member, the other end of the push rod extending out through the body portion, there being a socket in the body portion through which the rod extends, and a spring arranged in said socket 95 and acting to retain the rod in one position 100 of its adjustment.

4. A plug comprising a socket-engaging portion, a body portion, contacts carried by the socket-engaging portion, a locking member on the socket engaging portion movable at an angle to the longitudinal axis of the plug, a push rod movable longitudinally of the plug for actuating said locking member extending out through the body portion, and means for locking said push rod in one 110 position of its adjustment. 105

5. A plug comprising a socket-engaging portion, a body portion, contacts carried by the socket-engaging portion, a locking member on the socket engaging portion movable 115 at an angle to the longitudinal axis of the plug, a push rod for actuating said locking member extending out through the body portion, and a button swiveled upon the outer end of said rod, there being a bearing 120 on said body portion with which said button is adapted to engage in one position of adjustment of the button to lock the rod against inward movement, for the purpose 125 described.

6. A plug comprising a socket-engaging portion, a body portion, contacts carried by the socket-engaging portion, a locking member on the socket engaging portion movable 130 at an angle to the longitudinal axis of the

plug, a push rod for actuating said locking member extending out through the body portion, and a button swiveled upon the outer end of said rod, there being an inclined bearing on said body portion with which said button is adapted to engage in one position of adjustment of the button to lock the rod against inward movement, for the purpose described.

10 7. A plug comprising a socket-engaging portion, a body portion, contacts carried by and fixed in relation to the socket engaging portion, one of said contacts being a threaded segment, a threaded segmental locking member carried by the plug-engaging portion and adapted to be adjusted at an angle to the longitudinal axis of the plug, a push rod movable longitudinally of the plug having its inner end connected to said segmental locking member and having the other end extending out through the body portion, and a spring acting to retain the rod in its outward position of adjustment.

20 8. A plug comprising a socket-engaging

portion, a body portion, contacts carried by 25 the socket-engaging portion, an adjustable locking member on the socket-engaging portion, a push-rod for actuating said locking member extending out through the body portion, resilient means acting upon said 30 push-rod to yieldably retain said locking member in one position of adjustment, and means for positively retaining said push-rod in one position of its adjustment.

9. A plug comprising a socket-engaging 35 portion, a body portion, contacts carried by the socket-engaging portion, an adjustable locking member independent of the contacts, a push-rod extending out through the body portion for actuating said locking 40 member, and means for locking said push-rod in one position of adjustment.

In testimony whereof I affix my signature in presence of two witnesses.
